UNITED STATES PATENT OFFICE.

CHARLES W. MORGAN, OF RACINE, WISCONSIN, ASSIGNOR TO GASOLINE TURBINE MOTOR COMPANY, OF RACINE, WISCONSIN.

ROTARY GAS-ENGINE.

1,309,767.

Specification of Letters Patent. Patented July 15, 1919.

Application filed August 20, 1915. Serial No. 46,468.

To all whom it may concern:

Be it known that I, CHARLES W. MORGAN, a citizen of the United States, and resident of Racine, in the county of Racine and State 5 of Wisconsin, have invented certain new and useful Improvements in Rotary Gas-Engines; and I do hereby declare that the following is a full, clear, and exact description thereof.

10 My invention refers to improvements in rotary gas engines of the character disclosed in a patent granted to me No. 1,113,234, October 13, 1914, for rotary gas engines.

15 The object of said invention is to simplify the motor throughout and especially with reference to insuring positive control of the working and compression pistons employed in said motor.

20 Other objects of my invention are to provide the oscillatory working pistons with means for yieldably holding the same in active and neutral positions, thereby permitting a slight amount of flexure to insure perfect seating contact between the stationary and movable elements of the engine.

To provide a yieldable link connection 25 between the compression pistons, whereby they are so associated under unitary control that movement of each piston of the series is dependent upon the movement of the other pistons and to also provide a certain per cent. of independent yield or flexure with relation to movement of the pistons whereby 35 perfect surface contact is had between the movable and fixed elements of the motor:

To provide an arrangement whereby 40 movement of the work pistons to operative position at the firing side of the engine procures a preponderance of weight at said side of the engine whereby a gravitational force is exerted which assists the operation of the engine.

With the above and other objects in view 45 the invention consists in certain peculiarities of construction and combination of parts as set forth hereinafter with reference to the accompanying drawings and subsequently claimed.

50 In the drawings—

Figure 1 represents a sectional elevation of a motor, embodying the features of my invention, the section being indicated by line 1-1 of Fig. 4;

55 Fig. 2, another sectional elevation of the

same taken upon a plane as indicated by line 2-2 of Fig. 4;

Fig. 3, still another sectional elevation, the same being also indicated by line 1-1 of Fig. 4, with the exception that certain of the parts are removed upon a plane back of the section line to more clearly illustrate details of construction;

Fig. 4, a cross-section of the motor, the section being indicated by line 4-4 of Figs. 65 1 and 3;

Fig. 5, an enlarged detailed sectional view taken through a portion of the shell and rotor, the section being indicated by line 5-5 of Fig. 2;

Fig. 6, a detailed face view of a tumber- 70 actuating rail with parts broken away and parts in section, and

Fig. 7, a detailed sectional elevation through the motor shaft showing a spark-timing mechanism of standard type employed in connection with the motor.

Referring by characters to the drawings, A represents a water-jacketed fixed shell having passages 2, 2' extending from the lower side portions thereof and forming at their inner ends fuel intake and exhaust ports 3, 3', respectively. The inner walls of the shell are formed with oppositely disposed concentric offset surfaces x, y, which are separated by concentric short-length surfaces of a corresponding lesser diameter than the first mentioned surfaces and constitute the equivalents of cylinder heads 4, 4'. The cylinder heads are merged into the outer concentric surfaces x, y, by gentle cam curves as shown.

A cylindrical rotor B is revolvably mounted within the fixed shell and its annular surface is accurately ground to engage the circular faces of the cylinder heads. Hence the rotor, in conjunction with the before mentioned offset portions of the shell, forms the equivalent of an explosion or working cylinder C, and a charging or compression cylinder D, constituting separate compartments. The cylinder head 4 is positioned intermediate of the intake and exhaust ports 3 and 3' and separates the suction end d of the compression cylinder D from the exhaust end e of the working cylinder C. The piston head 4' of the shell separates the compression end d' of the cylinder D from the firing end c' of the working cylinder C.

The head 4' is provided with an aperture 110

5', into which is fitted a suitable spark-plug 5, the same being positioned near the firing end e' of the working cylinder, as best shown in Fig. 2.

5 The peripheral wall of the rotor B is provided with three semi-circular cavities 6 for ground joint fit with a correspondingly shaped set of working pistons E, which pistons are of the butterfly type, whereby they 10 are practically balanced and when in their neutral positions they are nested within the annular surface of the rotor to form an unbroken contour with the exception that one wing e is slightly flattened upon its 15 face to permit the outer corner to engage the contracted end surfaces of the working cylinder, whereby friction is eliminated to a certain extent when the rotor is revolved in the direction of the arrow and the said 20 piston is being forced into its neutral position in order to pass under the head $4'$.

The work pistons rotate upon trunnions 7 that are positioned concentric with the axis about which the cavities 6 are described. 25 The extreme movement of each work piston is limited by a stop-key 7' which is seated within the bottom of the cavity and extended into a segmental recess 7'' that is formed in the bottom wall of said piston. A series 30 of tumblers 8 are pivotally mounted upon the opposite side walls of the rotor, near its axis of motion and each pair of tumblers is connected to a work piston by link 9, as best shown in Fig. 3. - The tension coiled 35 spring 9' is attached to each tumbler and to the rotor side-wall, the reflex action of which spring tends to force the work piston against the outer surface of the rotor, which forms one wall of the working cylinder or 40 compartment C, which movement is effected by the lever connections comprising a set of links or tumblers.

Positive control of each working piston is had by a fixed segmental track-rail 10. 45 Disposed about the axis of the rotor and concentric therewith, the inner surface of the track-rail being engageable by heel pins 11 that project from the tumblers, whereby the working pistons are held in closed positions as they travel beyond the field of the 50 work cylinder.

Each tumbler is also provided with a wiper-toe 12, which toe is adapted to engage a fixed stud 12' that projects inwardly 55 from the base 10' of the track-rail, said engagement being effected after the tumbler is freed from said rail, this movement occurring at the moment that the flattened surface e of the piston E leaves the piston-head 4', at which time an explosion occurs 60 to impart a working stroke to the work piston, as best shown in Fig. 2 of the drawings. Thus the work piston is not only positively forced out to effect a perfect 65 union with the outer walls of the working

piston, but the spring connection of said working piston also serves as a medium for imparting a yielding contact, whereby a perfect joint is maintained even though the parts should wear after continuous usage. 70

The rotor B is also provided with three radial slots 13, into which are slidably mounted compression pistons F. Each compression piston comprises the flat plate preferably made in two sections f , f' , which sections are doweled together and fastened by suitable screws f'' , whereby filler strips may be inserted to adjust for variation in the length of the pistons that may occur through wear. The outer corners of the 80 compression pistons are channeled out for the reception of T-shaped packing blocks 14, whereby the contacting faces of the movable and fixed units of the motor are packed and said blocks are held into contact with the fixed unit or walls of the motor by coiled springs 14', which coiled springs are seated in bored recesses back of said blocks. Thus the side edges and upper corner edges of the compression pistons are capable of taking up 85 wear automatically and the upper contact face of each piston is beveled to facilitate a perfect fit in connection with the outer surfaces of the compression cylinder D. The piston-plate f projects beyond the end faces of the rotor and the lower section f of each plate is slightly shortened to form a shoulder g , in connection with the upper section f' , which shoulder is bored longitudinally 90 for the reception of a spring-pressed plug 16. These series of plugs 16 exert constant pressure upon the outer face of a coupling ring 17, which ring is provided with curved slots 17' that are engaged by roller pins 18, 100 there being one of the same projecting from each end of the compression pistons, it being understood that a pair of said rings are employed. Hence it will be seen that the compression pistons so connected move in 110 and out under common control of the ring 17, while at the same time said pistons have a limited amount of yield or play, due to the spring-controlled plugs which are associated with the pair of coupling rings, whereby the 115 upper contacting faces of the pistons are held in ground joint union with the engaged outer surfaces d , y , d' , of the suction and compression cylinder D.

In assembling the motor parts described, 120 the working pistons and their lever connections are adjusted to the rotor end walls and the compression pistons being in place, the said end walls of the rotor are then fitted with segmental cover-plates 18', the same 125 being secured by bolts 18''. Radial edges of the cover-plates 18', together, form clearance slots for the protruding compression piston ends. The cover-plates 18' are suitably recessed on their back walls to form 130

- housings for the operating mechanism of the work pistons and said cover-plates are also provided with journal-apertures for the work piston trunnions 7 and at the same time the 5 cover-plates being in abutting engagement with the ends of the working pistons, they constitute end closures for the circular piston cavities 6. The pair of coupling rings 10 are next fitted to the roller-pins 18 and 15 associated spring plugs, which are carried by the compression pistons. Hence, as shown in Fig. 1 of the drawings, the slots 17' of the rings are of sufficient length and width to permit compensating independent 20 movement of the several pistons and the tendency of the spring plugs serves to hold the upper faces of the compression pistons in engagement with the outer wall of the compression cylinder. The coupling rings 25 are adapted to rotate and at the same time have a wabble motion relative to the axis of rotation of the rotor, which movement is had due to the fact that clearance for the rings is formed by recessing the outer faces 30 of the cover-plates 18', whereby said rings are upon approximately the same plane as the high faces of the assembled cover-plates. The open ends of the fixed shell are closed by companion water channel shell caps 19. 35 These caps form end walls for the piston chambers or cylinders against which the end edges of the compression pistons contact as they travel through the compression cylinder. The caps 19 are also provided 40 with inwardly offset segmental cams 20, which cams conform to the outer contour of the working cylinder C and the annular face of the rotor, which annular face comprises the cover-plate sectors that are secured 45 to the ends of the rotor, the same being upon the same plane and in ground joint engagement with the inner circular faces of the cams. It is manifest that the said segmental cams 50 restrict the width of a working cylinder relative to the width of the compression cylinder and it follows that the inner circular faces of the cams constitute guides for the outer edges of the compression pistons which engage the same when said pistons enter the 55 work cylinder, whereby they are held in their retracted or idle positions during that part of their cycle. When the work pistons are traveling through the working cylinder, the inner side surfaces of the segmental cams 20 form a tight joint in connection with the flush ends of said working pistons to prevent a leakage at this point. The base 10' of each segmental track-rail 10 is fastened 60 to the inner face of the associated shell cap 19 so as to vertically align said track-rail and its fixed stud 12' in position to be engaged by the work piston tumbler mechanism. The rotor B is carried by a shaft 21, the 65 same being journaled in boxes 21' with which the shell-caps are provided. Between each work piston and compression piston, the rotor B has formed therein a gas pocket B', which pockets are adapted to receive the successively compressed fuel charges as said 70 pockets travel under the head 4', it being understood that the pockets are in advance of the compression pistons, which pistons force the charges therein as they wipe downwardly at the tapered end of the compression cylinders in advance of their travel under the compression and explosion head 4'. As shown, one of the journal-boxes 21' carries contact pins 22, which pins are electrically connected to the spark-plug 5 and a 80 commutator ring 23 that is electrically connected to a source of energy is made fast upon the shaft having a brush 23', which successively engages the contact pins, whereby by a spark properly timed is generated to 85 ignite the successive charges of gas. The operation of the motor is practically the same as that described in connection with my patent previously referred to. The fuel charge enters through the port 3 in the partial vacuum formed back of the compression piston and a subsequent charge forward of said piston is compressed as the piston travels from the intake end to the compression end of the working cylinder. The compressed charge of gas in the pocket B', upon 90 entering the firing end of the working cylinder, is ignited by the spark-plug and one wing of the work piston being now in contact with the outer wall of the working cylinder, the exploded charge will exert force thereon, whereby a working impulse is imparted to the rotor, as said piston travels in the direction indicated by the arrows, it being understood that a movement of the working piston is controlled by the cam-rail and pin associated therewith, which pin engages the tumbler that is in link connection with the piston, whereby said piston is positively moved out by mechanical force and also by 100 spring force. 105 I claim: 1. In a rotary engine the combination of a shell provided with offset compression and working cylinders, division heads between the cylinders, a rotor engageable with the division heads, a series of oscillatory working pistons mounted within the rotor, and a series of reciprocative compression pistons mounted in said rotor, the rotor being provided with pockets between each working and compression piston; the combination of a pair of circular fixed rails positioned at reciprocal ends of the rotor, a series of tumblers in pivotal union with the ends of said 115 rotor engageable with the rail, and a link connection between pairs of said tumblers and the ends of the working pistons. 120 2. In a rotary engine the combination of a shell provided with offset compression and 130

- working cylinders, division heads between the cylinders, a rotor engageable with the division heads, a series of oscillatory working pistons mounted within the rotor, and a series of reciprocative compression pistons mounted in said rotor, the rotor being provided with pockets between each working and compression piston; the combination of spring-controlled tumblers carried by the 10 rotor, links connecting said tumblers and working pistons, and positive means for actuating the tumblers in the same direction as that exerted by their spring control.
3. In a rotary engine the combination of 15 a shell provided with offset compression and working cylinders, division heads between the cylinders, a rotor engageable with the division heads, a series of oscillatory working pistons mounted within the rotor, and 20 a series of reciprocative compression pistons mounted in said rotor, the rotor being provided with pockets between each working and compression piston; the combination of tumblers carried by the rotor in link connection with the working ends of the pistons, means for exerting a yielding pressure upon the said pistons, and means carried by the shell for imparting positive movement to the aforesaid pistons through their 25 tumbler connections.
4. In a rotary engine the combination of 30 a shell provided with offset compression and working cylinders, division heads between the cylinders, a rotor engageable with the division heads, a series of oscillatory working pistons mounted within the rotor, and a series of reciprocative compression pistons mounted in said rotor, the rotor being provided with pockets between each working 35 and compression piston; the combination of a series of tumblers in pivotal union with each end of the rotor, the tumblers being provided with heel-pins and wiper-toes, circular segmental rails carried by the shell for 40 engagement with the tumbler heel-pins, means extending from the shell for engagement with the tumbler wiper-toes, and a link connection between each pair of tumblers and the ends of the working pistons.
5. In a rotary engine the combination of 45 a shell provided with offset compression and working cylinders, division heads between the cylinders, a rotor engageable with the division heads, a series of oscillatory working pistons mounted within the rotor, and a series of reciprocative compression pistons mounted in said rotor, the rotor being provided with pockets between each working and compression piston; the combination of 50 a series of tumblers in pivotal union with each end of the rotor, the tumblers being provided with heel-pins and wiper-toes, circular segmental rails carried by the shell for 55 engagement with the tumbler heel-pins, means extending from the shell for engagement with the tumbler wiper-toes, a link connection between each pair of tumblers and the ends of the working pistons, and a spring connecting each tumbler and the 60 rotor to exert an expanding force upon the 65 working pistons.
6. In a rotary engine the combination with a shell having offset compression and working chambers, of a rotor disposed between the chambers, pairs of valves carried 70 by the rotor and movable to project at the periphery thereof and means for intermittently holding one valve of each pair against movement to projecting position, said means being operable coincident with movement of 75 the other valve of the pair to extending position.
- In testimony that I claim the foregoing I have hereunto set my hand at Milwaukee, in the county of Milwaukee and State of 80 Wisconsin, in the presence of two witnesses.
- CHARLES W. MORGAN.
